DESIGN FOR A GAME BOARD OR SIMILAR DEVICE

Hyman Schwartz, New York, N. Y.

Application April 15, 1935, Serial No. 56,380

Term of patent 7 years

To all whom it may concern:

Be it known that I, Hyman Schwartz, a citizen of the United States of America, whose post-office address is 1665 Weeks Ave., in the county of Bronx, city and State of New York, have invented a new, original, and ornamental Design for Game Board or Similar Device, of which the following is a specification, reference being had to the accompanying drawing, forming part thereof.

I claim:—

The ornamental design for a game board or similar device, as shown.

HYMAN SCHWARTZ.
